(57) **CLAIM**

The ornamental design for a timing chip wristband, as shown and described.

DESCRIPTION

FIG. 1 is a perspective view of a timing chip wristband in accordance with the present design;

FIG. 2 is a top view thereof;

FIG. 3 is a bottom view thereof;

FIG. 4 is a front view thereof, the front and rear views being identical; and

FIG. 5 is a side view thereof, the opposite side view being identical.

FIG. 6 is a perspective view of another exemplary embodiment of a timing chip wristband in accordance with the present design;

FIG. 7 is a top view thereof;

FIG. 8 is a bottom view thereof;

FIG. 9 is a front view thereof, the front and rear views being identical; and,

FIG. 10 is a side view thereof, the right side and left side views being identical.

The broken lines in FIGS. 1 and 2 illustrate portions of the timing chip wristband that form no part of the claimed design.
